UNITED STATES PATENT OFFICE.

FRANK G. VAUGHEN, OF SCHENECTADY, NEW YORK, ASSIGNOR TO
GENERAL ELECTRIC COMPANY, OF NEW YORK.

PREVENTING CREEPING IN RECORDING-WATTMETERS.

SPECIFICATION forming part of Letters Patent No. 678,075, dated July 9, 1901.

Application filed March 1, 1901. Serial No. 49,419. (No model.)

To all whom it may concern:

Be it known that I, FRANK G. VAUGHEN, a citizen of the United States, residing at Schenectady, county of Schenectady, State of New York, have invented certain new and useful Improvements in Preventing Creeping in Recording - Wattmeters, (Case No. 2,110,) of which the following is a specification.

This invention relates to recording electrical instruments, particularly such as recording-wattmeters. In this type of instrument there is a motor-driven counter, one motor element being energized by a potential circuit across the consumer's mains and the other by a field-circuit in series with the consumer's translating devices. In order to render these instruments accurate, it is common in the modern type to employ an auxiliary field-coil for the purpose of overcoming the starting-friction, thereby leaving the motor in a condition to operate the counter under light loads and reducing the percentage of inaccuracy; but it frequently happens that instruments of this kind are installed in places where the instrument is subjected to vibration, and it is noticed that under such circumstances the retarding effect of friction is reduced, causing the torque of the starting-coil to be more than is required to overcome friction. Under these conditions the motor may be kept in slow action under no load, thereby operating the counter when it should not register. Various devices have been suggested and many tried to overcome this difficulty; but since the degree of vibration is not uniform in all locations of service and since in many places a provision of this kind is not required at all none of the arrangements heretofore proposed have been entirely satisfactory. I cure the difficulty by providing the motor-damper by which its speed of movement is reduced with a detachable and adjustable iron armature placed on the damping-disk in operative relation to the damping-magnet. With such a device an inspector may easily correct the inaccuracy of any instrument showing a tendency to start at no load. The device may be easily applied by the inspector, being simply a small piece of iron in the form of a clip which may be slipped over the edge of the damper-disk and adjusted until a proper working relation is

produced for the conditions at the particular point where the meter is installed. This differs essentially in character from a magnetic piece permanently attached to the damper, 55 since in such a case a stalling effect when the iron comes in the neighborhood of the magnet-poles is exercised at all times and in all service conditions, which, as hereinbefore stated, is not a desirable condition. 60

My invention therefore comprises a meter-motor having mounted in operative relation to its rotary element a detachable retarding device periodically called into action during the rotation of the motor, so as to provide a 65 dead-point by which rotation is arrested when no load is on the circuit. It comprises also other more specific features the novelty of which will be pointed out hereinafter and will be definitely indicated in the appended 70 claims.

In the accompanying drawings, which illustrate one form of the invention, Figure 1 represents diagrammatically the well-known Thomson recording-wattmeter having my invention applied to the damping-disk. Fig. 2 is a plan view of the magnetic damper of such an instrument. Fig. 3 is a detail view showing a group of clips to prevent creeping in accordance with my invention. 75 80

I have shown in the drawings the anti-creeping device as mounted upon the damper-disk. This is, however, not absolutely essential, as my invention would equally include the mounting of a periodically-acting 85 retarding device of any character adapted to act upon the movable element of the motor, the essential feature of my invention residing in the fact that my device is detachable from the motor and adjustable thereon, so as 90 to render it applicable to a meter *in situ* at a point where correction is desired, thus admitting of the exercise of the experience and judgment of the inspector and permitting the application only to such instruments as require correction of this nature. 95

1 1^a represent the field-coils of a meter-motor of a recording-wattmeter in series relation to a group of translating devices 2, which represent a consumer's plant. The counter or 100 register has not been shown, as the construction of recording-wattmeters is well under-

stood by those familiar with the art. The potential circuit extending across the mains includes the armature of the motor and an auxiliary starting-coil in the field, as shown 5 at 3 3^a, to overcome the starting-friction of the moving parts.

4 represents the damping-disk, commonly made of a thin plate of copper mounted on the armature-shaft and revolving within the 10 field of a pair of permanent magnets 5 5^a, which act as a load on the motor and integrate the energy passing through the meter. When such an instrument is installed in a place where there is considerable vibration or 15 jarring, the armature may take a slow movement under the influence of the potential coils even when there is no load on the consumer's circuit and no lamps or other translating devices are in operation, thus operating the register and giving a false indication of the amount 20 of energy used by the consumer. This is commonly called "creeping." I correct the tendency by providing a small clip of magnetic material adapted to be slipped over the 25 edge of the damper-disk and adjusted in more or less close relation to the damper-magnets. Such a clip is shown in operative relation in Figs. 1 and 2 at 6. It is composed simply of a small piece of iron or steel and may be a 30 piece of bent iron wire adapted to be forced over the edge of the disk, the elasticity of the limbs clamping it firmly to the disk. The inspector may adjust it with relation to the permanent magnets until it arrests the creeping 35 tendency of the meter-motor. Being thus detachable and adjustable in its nature, it may be carried by the inspector in his pocket and applied to any instrument that needs correction.

40 I am aware that it has been proposed to provide on the damper of a meter-motor a piece of iron to periodically check creeping by the detaining action on said iron of the permanent magnets. Such devices have always;

however, so far as I know, been a permanent 45 part of the motor structure, thus applying to the entire product of a factory a correction needed only under particular conditions and when not needed introducing into the meter an element which interferes with its absolute 50 accuracy. As my device, however, is applied only to such instruments as need it, it is free from such an objection.

What I claim as new, and desire to secure by Letters Patent of the United States, is— 55

1. A meter-motor provided with a removable retarding device for periodically arresting the creeping of the motor.

2. A meter-motor provided with an adjustable and detachable magnetic retarding device to compensate for creeping.

3. A meter-motor provided with a magnetic damper having a detachable clip of magnetic material in operative relation to the damper-magnets.

4. A meter-motor provided with a magnetic damper having a detachable and adjustable clip of magnetic material in operative relation to the damper-magnets.

5. A meter-motor provided with a damper-disk revolving in a magnetic field and provided with a removable piece of iron adjustable with relation to the field.

6. A detachable retarding device for the damper-disk of a meter-motor, comprising a clip of magnetic material adapted to be secured to the edge of the disk.

7. A detachable spring-clip for the damper-disk of a meter-motor, comprising a piece of magnetic material adapted to be secured to the edge of the disk at different distances from its center.

In witness whereof I have hereunto set my hand this 27th day of February, 1901.

FRANK G. VAUGHEN.
